UNITED STATES PATENT OFFICE

91,662

DESIGN FOR A TEXTILE FABRIC OR THE LIKE

Franz Hoenig, New York, N. Y.

Application February 6, 1934, Serial No. 50,630

Term of patent 3½ years

To all whom it may concern:

Be it known that I, FRANZ HOENIG, a citizen of Switzerland, residing in the city of New York, county of New York, and State of New York, have invented a new, original, and ornamental Design for a Textile Fabric or the like, of which the following is a specification, reference being had to the accompanying drawing, forming a part thereof.

The figure is a plan view of a textile fabric showing my new design.

I claim:

The ornamental design for a textile fabric or the like as shown.

In testimony whereof I have signed this specification.

FRANZ HOENIG.
